UNITED STATES PATENT OFFICE.

JOSEPH BOYER, OF ST. LOUIS, MISSOURI, ASSIGNOR TO THE BOYER RAILWAY SPEED RECORDER AND INDICATOR COMPANY, OF SAME PLACE.

ADJUSTABLE PULLEY.

SPECIFICATION forming part of Letters Patent No. 395,208, dated December 25, 1888.

Application filed December 6, 1887. Serial No. 257,149. (No model.)

To all whom it may concern:

Be it known that I, JOSEPH BOYER, of the city of St. Louis, in the State of Missouri, have invented a certain new and useful Improvement in Pulleys, of which the following is a full, clear, and exact description, reference being had to the accompanying drawings, forming part of this specification, and in which—

Figure I is a side view of my improved pulley, which is formed in two parts. Fig. II is a face view showing the two parts separated. Fig. III is a section taken on line III III, Fig. I. Figs. IV and V are detail sections showing the groove of different widths.

My invention relates to sectional grooved pulleys; and my invention consists in features of novelty hereinafter fully described, and pointed out in the claims.

1 is the hub of my pulley; 2, the radial arms thereof forming the web or spider; 3, the inner rim having a flange, 5, formed with a beveled bearing-face, 5^a; and 4 the outer rim having a flange, 6, formed with a beveled bearing-face, 6^a. The inner rim, 3, has an external screw-thread, and the outer rim, 4, has an internal screw-thread fitting the external screw-thread of the inner rim. The outer rim, 4, is positively adjusted on and parallel with the inner rim, 3, by turning it so as to move it in or out to decrease or increase the distance between the beveled faces of the flanges 5 and 6, which form a V-shaped groove or channel, 7, between them.

8 is a belt supported on the beveled faces at any distance between the base and the periphery of the pulley. Turning the outer rim inward or outward increases or decreases

the width of the V-shaped groove or channel between the flanges, as shown in Figs. 4 and 5. The outer rim is held to any adjustment by 40 means of a suitable catch. I have shown a lever or dog, 9, pivoted by pin 10 to one of the arms 2 of the web or spider having a short arm, 11, against which presses a spring, 12, as shown in Fig. III. The long arm of the lever 45 or dog engages one of a series of notches, 13, in the rim 4, and holds the latter to any position to which it may be adjusted.

It will thus be seen that the diameter of the pulley so far as regards the bearing-surface 50 of the belt may be increased or diminished.

I claim as my invention—

1. A pulley comprising an inner rim having a flange formed with a beveled bearing-face, an outer rim having a flange formed with a beveled bearing-face, said rims having screw-threaded connection by which the rims are positively adjusted for increasing or decreasing the radius or pitch-line of the belt, and a locking device for holding the rims to their 60 adjustment, substantially as described.

2. A pulley comprising an inner rim provided with a threaded portion and having a flange formed with a beveled bearing-face, the outer rim provided with a threaded portion fitting over the threaded portion of the inner rim and a flange formed with a beveled bearing-face, and a spring-catch for holding the outer rim to its adjustment, substantially as described.

JOSEPH BOYER.

In presence of—

GEO. H. KNIGHT,
EDWD. S. KNIGHT.
